REGISTERING MECHANISM FOR COMPRESSOR OR LIKE APPARATUS

Application filed September 10, 1927. Serial No. 218,812.

My invention relates to registering apparatus, and especially to registering mechanism for machines in which a series of like operations occur, but in which some of the operations are ineffective and are, therefore, not to be registered, as is the case in continuously operated fluid motors, pumps, compressors and the like. It is an object of my invention to improve the efficiency and the construction of apparatus of this character.

In apparatus of the class described, various forms of pressure-responsive means have been provided for engaging the counter, or other registering device, for registering the effective strokes, or other operations of the apparatus, and, usually, mechanical means are provided for disengaging the registering mechanism. This method of procedure is undesirable for the reason that the pressure often varies considerably, and in some cases is actually made excessive to assure sufficient pressure in the event that some air leakage may occur. Inasmuch as the periods of operation of the registering mechanism are generally longer than the periods of non-operation, it will be apparent that the various conditions of pressure will produce unequal and unnecessary wear on bearings, and the like, unless rather elaborate mechanism is provided.

Furthermore, in the operation of pumping apparatus, such as air compressors and the like, it is desirable to know the volume of fluid handled. If the number of working strokes are known, this can readily be computed. Obviously, any registering mechanism employed for such service must be capable of registering only the effective strokes.

Air compressors and the like are often operated at constant speed, as by an electric motor, and the air pressure is controlled by opening and closing the inlet valve. In such a compressor, the pressure in the receiver chamber between the stages varies from a positive pressure to a partial vacuum, according to whether or not the compressor is pumping. Hence, the conditions of pressure in the receiver chamber may serve as indicia of the performance of the compressor.

More particularly, therefore, an object of my invention is to provide a register operating mechanism which shall be adapted to be engaged with the registering instrument by mechanical means, and which shall be adapted to be disengaged by pressure-responsive means, and to provide for actuating the pressure-responsive means from the receiver chamber of an air compressor.

Apparatus embodying features of my invention is illustrated in the accompanying drawings, forming a part of this specification, wherein:

Fig. 1 is a plan view of an air compressor; and,

Fig. 2 is a section on line II-II of Fig. 1. According to my invention, some simple mechanical means, such as a counterbalance, is provided for normally engaging the counting mechanism, and pressure-responsive means, as a fluid-actuated piston is provided for disengaging the counting mechanism and for holding it at the proper times. The use of a counter weight for effecting engagement of the counting mechanism insures that this engagement will always be made with the proper pressure and unnecessary wear thereby avoided.

The pressure-responsive means is connected to the receiver chamber, or to the inter-cooler, of a compressor, so that a reduction of pressure of the proper amount will overcome the effect of the counter weight and cause the piston to disengage the counter from the compressor. As the compressor resumes pumping, the pressure in the receiver chamber changes from a partial vacuum to a positive pressure, and thus, the piston of the pressure-responsive device becomes ineffective, and engagement of the counting mechanism is effected by the counterbalance.

Referring now to the drawings for a better understanding of my invention, I show a pumping apparatus such as the air compressor indicated generally at 10, comprising a low-pressure cylinder 11, and a high-pressure cylinder 12, which are connected by means of the receiver chamber 13. An inlet passage 11a is provided for supplying air to the cylinder 11, and a valve 11b.

serves to control the flow of air through such passage. An electric motor, or other suitable driving motor 14 is connected to a driving member such as the drive shaft 16, which 5 carries the cranks for operating the piston rods of the respective cylinders, the cranks being enclosed by the crank cases 17.

As previously explained, compressors of 10 this type are usually driven at a constant speed and the pressure is controlled by opening and closing the valve 11b for the inlet passage 11a of the low-pressure cylinder, it being understood that when the valve is 15 closed the compressor does no pumping and that continued operation during this period produces a partial vacuum in the receiver chamber 13.

In order to provide for determining the 20 amount of air or other fluid handled, it is necessary to provide means for registering the effective, or working strokes of the compressor. In the form of invention shown, these means comprise a counter 18, which is mounted on one of the crank cases and is 25 adapted to be actuated by a lever 19 which is connected to the counter by a chain or other flexible connection 21. The lever 19 has a fixed fulcrum 22 intermediate its ends and may be provided with a counterweight 30 23. A cam 24 on the shaft 16 is adapted to engage the lever 19, the latter being constantly urged in the direction of the cam by virtue of the counterweight. With this arrangement, on each revolution of the drive 35 shaft 16 the cam will depress the end of the lever 19 and actuate the counter 18 through the connection 21. It will thus be seen that the balanced lever 19 provides a simple and effective means for actuating a counter and 40 that the lever is always engaged with a constant, predetermined force and thus it is assured that minimum of shock and wear will occur.

In order to provide for registering only 45 the effective, or working, strokes on the counter 18, I provide pressure-responsive means, such as a cylinder 25 having a piston 26 therein which is connected to the lever 19 by a suitable connection, such as a chain 27. In 50 the form shown, the upper or the rod side of this piston is exposed to atmospheric pressure, while the lower side of the piston is subjected to the pressure in the receiver chamber 13 by means of the tube 28 which connects the receiver chamber with the lower 55 end of the cylinder 25. If for any reason the compressor should become ineffective, the pressure within the receiving chamber 13, and consequently the tube 28 and the lower 60 part of the cylinder 25, would fall below that of the atmosphere. The unbalanced pressure condition within the cylinder 25 will cause the piston 26 to move downward and carry with it the lever 19. It will thus be 65 seen that a decrease in pressure which may

be of a variable amount in the chamber 13 is made to render the means for actuating the counter 18 ineffective.

In the accompanying drawings I have shown the tube 28 as being connected to the receiver 13. It is to be observed, however, that insofar as certain aspects are concerned, my invention is not so limited, for such tube might equally as well be connected to the compressor at any point where a vacuous condition may exist, for example, such tube may be connected to the inlet passage 11a.

While I have shown my invention embodied in an air-compressing apparatus, it will be obvious that it is not limited in its application to pumping apparatus for compressible fluids, but that it is also well adapted to various forms of pumps for non-compressible fluids. Furthermore, it will readily be seen that my invention may be embodied in a rotary, as well as in reciprocating pumps. In the latter case, the counting mechanism would be operated by a cam, such as the cam 24, and the pressure-responsive means would be operated from the receiver chamber between the stages in a manner similar to that described in connection with the air compressor.

While I have shown my invention in one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. The combination with compressor apparatus of the continuously-operated type wherein the output is controlled by the shutting off of the supply passage with a resulting vacuous condition in such apparatus, of a register, means for operating the register simultaneously with the compressor, and means responsive to a drop in pressure in the compressor apparatus for rendering the register operating mechanism ineffective.

2. The combination with a compressor wherein the output is controlled by the shutting off of the supply passage with a resulting vacuous condition in such apparatus, and means including a power operated shaft for continuously operating the compressor, of a register, means driven by said shaft for operating the register, and means responsive to a drop in pressure in the compressor for rendering the register operating mechanism ineffective.

3. The combination with a compressor apparatus of the type wherein the output is controlled by the shutting off of the supply passage with the resulting vacuous condition in such apparatus and means including a power

operated shaft for continuously operating the compressor, of a register, a lever for operating said register, an eccentric device driven by said shaft and normally in engagement with said lever for imparting movement thereto, and means responsive to a drop in pressure in the compressor apparatus for disengaging the lever and eccentric.

4. The combination with a compressor including high pressure and low pressure stages and a receiver chamber connecting the stages, and means comprising a power driven shaft for operating the two stages, of a register, a counter-weighted lever for operating said register, an eccentric device driven by said shaft and operatively engaging said lever, and means responsive to a predetermined drop in pressure in the receiver chamber for disengaging the lever and cam device.

In testimony whereof, I have hereunto subscribed my name this sixth day of September, 1927.
